UNITED STATES PATENT OFFICE.

DE WITT C. VOUGHT, OF WILLIAMS BRIDGE, NEW YORK.

FLYING-MACHINE.

1,004,117.

specification of Letters Patent. Patented Sept. 26, 1911.

Application filed April 21, 1910. Serial No. 556,692.

To all whom it may concern:

Be it known that I, DE WITT C. VOUGHT, a citizen of the United States, and residing at Williams Bridge, in the county of New York and State of New York, have invented certain new and useful Improvements in Flying-Machines, of which the following is a specification, such as will enable those skilled in the art to which it appertains to make and use the same.

This invention relates to flying machines, and particularly to what are known as aeroplanes; and the object thereof is to provide a flying machine of this class which is simple in construction and operation and which is so constructed as to be automatically balanced and held in proper position at all times; and with this and other objects in view the invention consists in a machine of the class specified constructed as hereinafter described and claimed.

The invention is fully disclosed in the following specification, of which the accompanying drawing forms a part, in which the separate parts of my improvement are designated by suitable reference characters in each of the views, and in which:

Figure 1 is a perspective view of my improved flying machine; Fig. 2 a front end view thereof, and:— Fig. 3 a sectional side view.

In the practice of my invention I provide a cylindrical casing *a* which may be constructed in any desired manner, as for instance of aluminum suitably reinforced, or said casing may consist of a framework covered with canvas, oiled silk or like material.

Passing around each end portion of the cylindrical casing *a* is a band *b*, the bottom part *b*² of which is set off from said casing so as to form segmental supports from which is suspended a car *c*. The car *c* is suspended from the segmental support *b*² by stirrups *c*², which are free to slide on said segmental supports *b*² and as thus suspended, when the machine is in operation, the car *c* will always be maintained by gravity in a vertical plane passing through the axis of the casing *a*.

At each end of the casing *a* is a spider work *a*² in which is mounted a central longitudinal propeller shaft *d* provided, in the form of construction shown, with end propellers *d*¹, and a central propeller *d*³, all of which are within the casing *a* and the top portion of said casing is provided with

raised hood members *a*³ which open upwardly and forwardly as shown at *a*⁴. Placed in the car *c* is a suitable motor *d*⁴, the shaft *d*⁵ of which extends longitudinally and centrally of one end portion of the car *c* and is geared in connection with the rear end of the propeller shaft *d* by a sprocket or drive chain *d*⁶, which is mounted on sprocket wheels *d*⁷ and *d*⁸ mounted respectively on the motor shaft *d*⁵ and propeller shaft *d*.

At each side of the cylindrical casing *a* are wings *e* which are rigidly connected with said casing at *e*², this connection being preferably made by dividing the bands *b* into separate parts and securing said parts to the framework of the wings *e*, and said wings preferably consist of rigid frames *e*³ and a body portion *e*⁴ of canvas, silk or other suitable material secured in or to said frames.

Secured to the outer edge portions of the frames *e*³ of the wings *e* and to the upper sides thereof are rods *f* which pass over and transversely of the cylindrical casing *a* and through keepers *f*² secured thereto and in which said rods are secured by soldering or otherwise, and similar rods *f*³ are secured to the bottom of the outer edge portions of the frames *e*³ of the wings *e* and pass transversely of and beneath the cylindrical casing *a* and through the keepers *f*⁴ secured thereto as shown in Fig. 1 and in or to which the rods *f*³ are secured, but my invention is not limited to this method of connecting the rods *f* and *f*³ to the cylindrical casing *a* and this connection may be made in any desired manner.

Hinged to the outer edge portion of the wings *e* are supplemental wing members *g*, the connection being shown at *g*² and the supplemental wing members *g* also consist in the form of construction shown of frames *g*³ filled in with canvas, silk or other suitable material *g*⁴, and passing through the outer edge portion of the frames *g*³ and near the end portions thereof in the form of construction shown are pins or rods *g*⁵, with the upper end portions of which are connected cords *h* which pass over the top of the cylindrical casing *a* in opposite directions, and through keepers *h*² secured thereto and through which said cords are free to slide, and the ends of the cords *h* are secured to the opposite sides of the car *c* as shown at *h*³, the cord *h* which is secured to the right hand supplemental wing member *g* being secured to the left side of the car *c* while

the cord h which is secured to the left hand supplemental wing member g is secured to the right side of the car c .

Connected with the lower ends of the pins 5 or rods g^3 are spiral springs i to which are secured rods i^2 which are secured to the cylindrical casing a at i^3 or preferably to the bands b which pass around the end portions of said cylindrical casing.

10 It will be observed that four of the rods f^3 are employed for connecting the outer edge portions of the main wings e with the bottom of the cylindrical casing a together with four of the rods f , but my invention is 15 not limited to the number of these rods as will be readily understood.

With the method of suspending the car c from the cylindrical casing a , as shown and described and the method of hinging the 20 supplemental wings g to the main wings e , and the method of using the cords h and the springs i and rods i^2 as herein shown and described it will be seen that if at any time the machine should turn laterally, the car 25 c will also swing laterally and maintain its position in a vertical plane passing through the axis of the cylindrical casing a , and this operation of the car c will raise one of the supplemental wings g according to the direction in which said car swings, and this will tend to hold the machine's equilibrium and keep it in proper position at all times, and in Fig. 2 of the accompanying drawing 30 I have shown or indicated this operation, the normal position of the machine and especially the wings thereof being indicated in dotted lines while one of said wings, that at the right, is raised and it will be understood that the springs i and rods i^2 serve 35 to return the supplemental wings g to their proper position at all times and to hold them in said position.

The rear end portion of the machine is provided with a vertically arranged rudder j 40 which is supported by forked-shaped brackets j^2 secured to the top and bottom of the rear end portion of the cylindrical casing a , and the rudder j is operated by cords j^3 connected with the outer edge portion thereof as shown at j^4 and passing along the opposite sides of the rear end portion of the cylindrical casing a and around pulleys j^5 secured thereto and down into the car c , as shown at j^6 and by means of these cords j^3 the rudders j may be manipulated by the occupant of the car as will be readily understood.

At the front end of the machine is a nose or guide plane k pivoted in brackets k^2 similar to the brackets j^2 , said brackets k^2 being secured to the front end portion of the cylindrical casing a , and connected with the front or free edge portion of the nose or guide plane k as shown at k^3 are cords k^4 , 65 one of which is passed around a pulley k^5 at

the top of the front end portion of the cylindrical casing a , and the other around a pulley k^6 at the bottom of the front edge portion of the cylindrical casing a and these cords k^4 are also passed down into the car c 70 as shown at k^7 and by means thereof the nose or guide plane k may be turned in either direction or manipulated as will be readily understood.

The car c may, if desired, be provided 75 with wheels m in the usual manner so as to facilitate the starting of the machine or the landing or lighting thereof.

In the operation of this machine the air passes backwardly through the cylindrical 80 casing a and also downwardly and backwardly through the hoods a^3 and the propellers d^2 and d^3 operating on this air to propel the machine in the usual manner and by inclosing the propellers in the cylindrical 85 casing a so that they operate only on air passing therethrough in the manner described I avoid the side or lateral currents which usually interfere with the propellers of machines of this class and also interfere 90 with the operation of the machine and render said operation uncertain and dangerous.

It will be understood that the machine is started in the same manner as others of its class and it will also be understood that the 95 main wings e and supplemental wings g constitute the main planes of my improved flying machine, and the supplemental wings or planes g being, as hereinbefore described automatically operated, my improved flying 100 machine will maintain its proper position and equilibrium in the air, and by suspending the car c below the cylindrical casing a , the center of gravity of the machine is lowered and this also aids the machine in 105 maintaining its proper position in the air.

The hinge connection at g^2 between the supplemental wing members g and the main wing members e is made by means of plates n secured to the main wing members e , and 110 to which the supplemental wing members g are pivoted at n^2 , and secured to the bottom of the supplemental wing members g are plates n^3 the free ends n^4 of which overlap the bottom of the main wing members e and 115 this construction permits the supplemental wing members g to move upwardly by preventing them from moving downwardly below the plane of the main wing members e .

The hood members a^3 which open upwardly and forwardly serve, as will be understood, to lift or raise the machine, and these hoods serve also to supply an additional amount of air to be operated upon by the rear propeller d^2 and central propeller d^3 , and both of these operations of the hood members a^3 and the results produced thereby facilitate the operation and control of the machine.

I have also indicated at m wheels which 120

may be applied to my improved flying machine in the usual manner, or as to other machines of this class, but these wheels form no part of my invention.

5 Having fully described my invention, what I claim as new, and desire to secure by Letters Patent, is:—

1. In a flying machine, a cylindrical casing, a shaft mounted centrally and longitudinally therein and provided with propellers, a car suspended from said casing and adapted to swing laterally by gravity, a motor mounted in said car and geared in connection with said propeller shaft, main wings secured to the opposite sides of said casing, supplemental wings hinged to the outer or free edges of the main wings and devices connected with said car and with said supplemental wings whereby when said car swings laterally said supplemental wings will be raised and lowered.

2. In a flying machine, a casing, a propeller shaft mounted longitudinally therein and provided with propellers, a car suspended from said casing and adapted to swing laterally by gravity, wings secured to the opposite sides of said casing and projecting therefrom, supplemental wings hinged to the outer edge portions of said first named wings, springs connected with the supplemental wings on the lower side thereof, rods connected with said springs and with the bottom portions of said casing and cords connected with the supplemental wings on the top side thereof, said cords being passed over said casing in opposite directions and connected with said car.

3. In a flying machine, a cylindrical casing open at both ends and the top portion of which is provided with hoods which open upwardly and forwardly, a propeller shaft mounted centrally and longitudinally in said casing and provided with propellers, a car suspended from said casing and adapted to swing laterally by gravity, main side wings connected with said casing and supplemental side wings connected with said

main wings and with said car, whereby the movement of said car will also operate said supplemental wings.

4. In a flying machine, a cylindrical casing open at both ends and the top portion of which is provided with hoods which open upwardly and forwardly, a propeller shaft mounted centrally and longitudinally in said casing and provided with propellers, a car suspended from said casing and adapted to swing laterally by gravity, main side wings connected with said casing and supplemental side wings connected with said main wings and with said car, whereby the movement of said car will also operate said supplemental wings, said casing being also provided at the front end thereof with a horizontally arranged nose or guide plane, and at the rear end thereof with a vertically arranged rudder.

5. In a flying machine, a cylindrical casing open at both ends and otherwise closed except the top portion thereof which is provided with openings having hoods which extend upwardly and forwardly, and a propeller shaft mounted centrally and longitudinally in said casing and provided within said casing with propellers.

6. In a flying machine, a cylindrical casing open at both ends and the top of which is provided with openings having hoods which extend upwardly and forwardly, a propeller shaft mounted centrally and longitudinally in said casing and provided with propellers, means for operating said shaft, side wings connected with said casing and a car suspended from said casing and adapted to swing laterally by gravity.

In testimony that I claim the foregoing as my invention I have signed my name in presence of the subscribing witnesses this 19th day of April, 1910.
